GOALKEEPER'S ICE HOCKEY BANDY

Raimo Matilainen, Hyvinkaa, Finland, assignor to
Montreal-Urheilu Oy, Tampere, Finland

Filed Jan. 23, 1974, Ser. No. 435,665

Claims priority, application Finland Aug. 10, 1973

Term of patent 14 years

Int. Cl. D21—02

U.S. Cl. D34—5 BC

FIG. 4

FIG. 5

FIG. 6

FIG. 1 is a side view of a goalkeeper's ice hockey bandy embodying the new design;

FIG. 2 is a rear view thereof;

FIG. 3 is a front view thereof;

FIG. 4 is a top view thereof;

FIG. 5 is a bottom view thereof; and

FIG. 6 is a perspective view thereof.

The characteristic feature of my design resides in the combination of the concave base portion of the shaft and the curved blade as shown.

I claim:

The ornamental design for a goalkeeper's ice hockey bandy, substantially as shown and described.
